DESIGN FOR AN ASH TRAY

Ray R. Hutcheson, Kew Gardens, N. Y., assignor
to Diecasters, Inc., New York, N. Y., a corpora-
tion of New York

Application December 16, 1935, Serial No. 60,091

Term of patent 7 years

To all whom it may concern:

Be it known that, I, Ray R. Hutcheson, a citizen of the United States, residing in Kew Gardens, county of Queens, and State of New York, have invented a new, original, and ornamental Design for Ash Trays, of which the following is a specification, reference being had to the accompanying drawing, forming a part thereof, in which:

Fig. 1 is a front elevational view of the ash tray showing my new design.

Fig. 2 is a plan view of Fig. 1.

I claim:—

The ornamental design for an ash tray, substantially as shown.

Signed at New York, in the county of New York and State of New York, this 30th day of November, 1935 A. D.

RAY R. HUTCHESON,
